DEVICE FOR MAKING ROSETTE-LIKE ARTICLES

Herbert Cottrell, Point Pleasant, N. J.

Application November 10, 1943, Serial No. 509,938

3 Claims. (Cl. 28—15)

This invention relates to a device for manually producing rosette-like articles formed by winding a strand or strands of thread or wool over the device and then removing the strand when the pattern is finished by releasing the loops of the article. The articles are representative of flowers such as daisies formed by radial loops gathered at the center. The articles are used singly or are sewed together to form larger articles such as table covers, sweaters, bed spreads and other articles. The present invention is an improvement over a device illustrated and described in a former patent of applicant, issued August 20, 1935, No. 2,011,617. The article produced is substantially the same as that formed on the device shown in the above patent.

The object of the invention is to provide a device made of separable parts which are easily manipulated and which, when assembled provide a ready means for receiving wool or similar strands. The finished article is released from the device by simply separating the parts and lifting the completed article from the device.

The device has the advantage of being small and compact, and is also cheaply manufactured as it comprises only two parts easily assembled and easily separated.

The invention is illustrated in the accompanying drawing in which Figure 1 is a top view of a device embodying the invention, and also showing a strand in the initial turns taken to form the article. Figure 2 is a central cross-section of the device shown in Figure 1. Figure 3 is a view of a finished article after it is removed from the device.

The device comprises two readily connected and easily separated parts, a disc-like member and a stem or pin to be attached to the bottom of the member.

The disc-like member is shown at 10 and may be made of any desirable material but is preferably made of wood, although plastic or metal may be used. The disc is provided with notches at its rim. Such notches or indentations are preferably provided by placing radially arranged grooves 11 in the top face of the member. The grooves 11 are preferably deepest at their outer ends and tapered toward the center of the member. The advantage of this will be set forth hereinafter.

The disc is provided with a pin 13 which is secured to the under side of the disc 10. As the pin is adapted to be readily removed it is preferably held in place by means of a tight fit on

the pin in the recess 14. The recess 14 is usually placed in the center of the bottom of the disc. Other means may be employed to detachably attach the pin to the disc.

5 The device is used by assembling the disc and the pin and then winding a strand over and under the disc, each turn under the disc being passed around the pin 13. One method of winding is shown in Figure 1. The strand 15 is held by the thumb at 1, then passed over the disc in a recess or groove 11 then under the disc as at 2, then around the pin 13 as at 3 then to the next recess 11 at 4, across the disc at 5 and then under the disc at 6 around the pin 13 and then 15 to the recess at 7 and so on around the disc. After all the loops are finished the two ends of the strand and the central part of the crossed strands are gathered by stitching 16 to form a rosette.

20 After the rosette is thus secured the pin 13 is removed and the loops 17 are released from the pin and the rosette can be straightened out and is ready for use as a unit or to be connected to with others to form a larger article.

The form shown in Figures 1 and 2 with the tapered slots 11 terminating short of the center of the top of the disc is designed to facilitate the sewing of the center of the rosette as the central part of the strands are raised above those parts in the grooves 11 and the sewing of the central part is facilitated.

I claim:

1. A device for forming rosette-like articles comprising a circular flat member having radially arranged grooves in its top face and extending to the rim, the grooves being deepest at the rim and tapering toward the center of the member, the member having a recess in the bottom face thereof, and a pin fitting in the recess and readily removable therefrom.

35 2. A device for forming rosette-like articles comprising a flat circular member having radially extending tapered grooves in its top face, and a pin removably secured to the bottom face thereof.

40 3. A device for forming rosette-like articles comprising a member having grooves in its top face extending to and being deepest at the rim and tapering toward the center of the member, the member having a recess in the bottom face thereof, and a pin fitting in the recess and readily removable therefrom.

HERBERT COTTRELL.
